CLAIM

The ornamental design for a colorful stone game set, as shown and described.

DESCRIPTION

FIG. 1 is a front perspective view of a first embodiment of a colorful stone game set showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear perspective view thereof.

FIG. 9 is a front perspective view of a second embodiment of the colorful stone game set.

FIG. 10 is a front view thereof.

FIG. 11 is a rear view thereof.

FIG. 12 is a left side view thereof.

FIG. 13 is a right side view thereof.

FIG. 14 is a top view thereof.

FIG. 15 is a bottom view thereof.

FIG. 16 is a rear perspective view thereof.

FIG. 17 is a front perspective view of a third embodiment of the colorful stone game set.

FIG. 18 is a front view thereof.

FIG. 19 is a rear view thereof.

FIG. 20 is a left side view thereof.

FIG. 21 is a right side view thereof.

FIG. 22 is a top view thereof.

FIG. 23 is a bottom view thereof; and,

FIG. 24 is a rear perspective view thereof.
